UNITED STATES PATENT OFFICE.

THEODORE J. KING, OF WASHINGTON, DISTRICT OF COLUMBIA.

FARE-RECEIVER.

SPECIFICATION forming part of Letters Patent No. 511,703, dated December 26, 1893.

Application filed June 26, 1893. Serial No. 478,844. (No model.)

To all whom it may concern:

Be it known that I, THEODORE J. KING, a citizen of the United States, residing at Washington city, in the District of Columbia, have 5 invented certain new and useful Improvements in Fare-Receiver; and I do declare the following to be a full, clear, and exact description of the invention, such as will enable others skilled in the art to which it appertains 10 to make and use the same.

This invention relates to a device more particularly designed for use in the office of a street or other railway, and it has for its prime object to provide a device or apparatus by 15 which the conductor of a car may safely deposit his receipts after each trip or series of trips without the employment of a receiving clerk or attendant so that an accurate and safe account may be kept by each conductor 20 of a car for the day's receipts; the construction being such that the conductor or conductors, without being permitted to see the receptacle or holder for the receipts, can be assured that without negligence or carelessness 25 on their part, the fares and receipts will be deposited into a box or receptacle set apart for the particular runs, and with this end in view, I provide numbers, marks, or characters upon the face of the apparatus indicative of 30 correspondingly numbered receptacles arranged within the case, and an operating handle or lever, through the manipulation of which the box or receptacle of the revolving series, may have a compartment of a number 35 corresponding with the number or character on the face, brought to the receiving slot or point.

Other objects and advantages will appear from the following description and claims 40 when taken in connection with the annexed drawings, in which—

Figure 1, is a plan view of my improved device. Fig. 2, is a vertical, transverse, sectional view of the same. Fig. 3, is a vertical, 45 sectional view taken in the plane indicated by the dotted line x, x , on Fig. 2. Fig. 4, is a plan view of the upper receiver. Fig. 5, is a similar view of the lower receiver, and Fig. 6, is an enlarged, perspective view of one 50 of the upper and lower receivers, and the conducting tube, with parts broken away.

Referring by letter to said drawings: A, in-

dicates the casing, which is here shown as of a rectangular form in outline, although it is obvious that it may be of any suitable configuration, and for the purpose of safety, this casing may be of such a construction as the ordinary burglar and fire-proof safe. On the top a , of this casing I provide a vertical, annular flange b , and notch the flange at suitable intervals as shown at c , or provide it at such points with suitable stops. I provide a number or character at each notch or stop for a purpose which will be presently described. 55

B, indicates a vertical, rotatable shaft. 60 This shaft is stepped at its lower end in a suitable bearing d , in the bottom or floor of the casing, and its opposite or upper end passes through a hole or aperture e , in the center of the top of the casing. Secured to 65 this shaft so as to rotate therewith, is a cylindrical box or holder which is divided into compartments and designed to receive through a tube or conveyer C, leading from a slot f , in the top of the casing, and conduct the fares 70 or receipts into such box or holder. The compartments of the revoluble receiver are so numbered or marked, that when the receiver has been rotated so that compartment No. 1, for instance, should be brought beneath the 75 slot in the casing, it will be so indicated by the number upon the top of the casing. This revoluble receiver which is secured to the shaft, is divided by vertical, radial partitions, as I find that this is the most convenient form 80 of construction, but with a view of economy and utilization of space, I have provided receivers of a peculiar construction, and while I do not wish to be understood as confining myself to the precise form or manner of construction which I have shown in the present embodiment of my invention, I shall now 85 proceed to a detail description of such construction. 90

D, indicates a box or receiver which is 95 shown as of a cylindrical form in cross section. This box is divided into compartments g , by vertical, radial partitions h , and has a vertical, concentric aperture i , to receive the vertical shaft b , to which it is suitably secured. It will be observed that this receiver is secured to the lower portion of the shaft. 100

E, indicates an upper receiver which is of a similar form in outline, and is divided into

compartments *k*, by vertical, radial partitions *l*, and in one of each of the outer corners of these compartments *k*, I provide a chute *m*, which is designed to come beneath the tube 5 *C*, and deposit into the respective compartments *g*, of the lower box or receiver.

The casing is provided with a suitable door *F*, and the outer faces of the respective compartments are marked by numbers or other 10 characters, as shown, so that when the door has been opened, the attendant or other authorized person, may inspect and remove the fares from the compartments. The upper box or receiver carrying the chutes is secured 15 to the shaft in a manner similar to the lower receiver, so that as the shaft is rotated, the various receivers will move simultaneously.

G, indicates a handle. This handle is provided with a suitable grasp *n*, and a depending lug or detent *p*, which is designed to enter the notches *c*, or engage the stops on the vertical, annular flange *b*. This handle which also serves as an indicator, is pivotally secured at its inner end to the upper end of 25 the rod or shaft *B*, so that as said handle is rotated or partly rotated over the flange, it will correspondingly rotate or partly rotate the receivers secured to the shaft. The tube *C*, may be of any suitable construction, and 30 depends from the slot *f*, to a suitable distance within the casing so as to discharge into the desired compartments of the receivers.

It will be observed that the internal, aggregate area of the compartments *k*, and the 35 chutes *m*, is equal to the internal area of the segmental or radial compartments *g*, of the lower receivers, and said receivers have such segmental or radial compartments arranged truly above each other.

40 *H*, indicates a horizontal plate. This plate is provided with a marginal, vertical flange or band *q*, and the band is provided with numbers or characters as shown, corresponding with the respective compartments of the receiver *D*, so that in placing the receivers, the marked plate will serve as an indicator for the proper adjustment of the parts.

I, indicates a horizontal plate, which is secured to the revoluble shaft and upon which 50 the upper revoluble receivers rest. This upper plate is also provided with a vertical, marginal flange or other suitable means, and bears marks or characters, as shown to correspond with those of the receptacles of said 55 upper receiver, and the chutes which pass through the compartments of the upper receivers. This plate *I*, is provided with openings *s*, of a shape in outline corresponding with a cross section of the chutes, and said 60 chutes depend below the plate, as indicated at *t*, so as to convey the fares into the proper compartment of the lower receiver. By this means it will be seen that after either of the receivers have been removed from their proper 65 positions, they can be adjustably replaced without any danger of misplacing the upper receiver with respect to the lower one, and

both with respect to the numbers or characters on the top of the casing.

In operation, it is simply necessary for a 70 conductor or other person placing his receipts within the casing or safe, to grasp the handle and rotate the shaft *B*, until the detent or lug of the handle has been brought into the desired notch or stop on the vertical flange. 75 This movement will bring a compartment of the receiver of a number corresponding with the number or character at the notch in which the lever has been placed, directly below the slot in the top of the casing or tube *C*, so that 80 as the party deposits the fares in the slots, such fares will be properly discharged into the receptacle beneath.

It will be seen that when the handle has been turned so as to bring a chute *m*, directly 85 below the tube or conveyer *C*, such deposits as are then made, will be directed into one of the compartments *g*, of the lower receiver, while by turning the handle a little farther so as to bring the lower end of the tube *C*, clear 90 of the chute *m*, such deposits as may then be made, will be conducted by said tube into one of the compartments of the upper receiver.

It is obvious that in some cases a single cylindrical box might be employed having segmental receptacles formed by vertical, and radial partitions, and thus simplify the construction, and I am aware that many other changes can be made in the construction and 100 arrangement of the parts, without departing from the spirit of my invention.

Having described my invention, what I claim is—

1. A receiver for the purpose described, 105 comprising a casing having a receiving slot or aperture in its top, a revoluble box divided into compartments and each compartment bearing a mark or character, the casing having marks or characters displayed to correspond with the marks or characters of the compartments in the receiver and an indicator adapted to rotate said receiver and be moved around the path of the marks or characters on the casing, whereby when the indicator has been turned to rotate the receiver, 115 it will bring a compartment to the receiving slot bearing a mark or number corresponding with the mark or number to which said indicator has been brought on the casing.

2. The combination with a casing having the vertical, annular flange on its upper side provided with notches or stops at pre-determined points, and also provided with numbers or characters at such notches or stops, 125 and furthermore provided with a receiving slot or aperture; of a revoluble receiver secured to an operating shaft and divided into compartments which bear numbers or characters corresponding with those on the casing, and an indicator adapted to rotate said shaft and receivers and engage the notches or stops in the flange, substantially as specified.

3. In a device of the character described, the combination with a casing having a receiving slot or aperture; of a vertical shaft journaled therein, an operating handle to serve the additional function of an indicator secured to said shaft, the lower cylindrical box divided into compartments and secured to the shaft, and the upper cylindrical box divided into compartments and also having chutes or conveyers through said compartments to discharge into the compartments of the lower box, substantially as specified.

4. The improved fare receiver described, comprising the outer casing, having the receiving slot or aperture in its top and also having the vertical, annular flange provided with notches and a number or character at each notch, the vertically-disposed, rotatable shaft, the handle secured to the upper end of said shaft for rotating the same and adapted to engage the notches, the lower plate secured to the shaft and having the marginal flange bearing numbers or characters, the box

divided into compartments by vertical and radial partitions, and arranged upon said plate, and the upper plate having a similar marginal flange also provided with characters or numbers, and the box placed on said plate and divided into compartments by vertical and radial partitions, and such compartments having chutes passing through them, and through the supporting plate, the whole adapted to operate in such a manner that when the indicating handle has been moved and placed in one of the notches of the vertical flange, a compartment of one of the receivers bearing a corresponding number or character will be brought to receive from the slot in the casing, substantially as specified.

In testimony whereof I affix my signature in presence of two witnesses.

THEODORE J. KING.
